Des. 221,105
Patented July 6, 1971

221,105

FRONT PANEL FOR TRANSOM LIGHT FOR BOATS OR THE LIKE

Donald E. Stewart, Grand Rapids, Mich., assignor to
Attwood Corporation, Lowell, Mich.

Filed Sept. 11, 1969, Ser. No. 19,102

Term of patent 14 years

Int. Cl. D12—99; D26—02
U.S. Cl. D48—32

FIG. 1.

FIG. 2.

FIG. 3.

FIG. 1 is a perspective view of the front panel for transom light for boats or the like embodying my design; FIG. 2 is a side elevational view thereof; and FIG. 3 is a front elevational view thereof.

The interior of the front panel for transom light for boats or the like substantially follows the surface contours of the exterior as best seen in FIG. 1.

I claim:

The ornamental design for a front panel for transom light for boats or the like, substantially as shown and described.
